Duell, Warfield & Dugg
ATTORNEY

UNITED STATES PATENT OFFICE.

GEOLEADYS GALE THOMPSON, OF ST. LOUIS, MISSOURI.

GARMENT.

1,399,825.

Specification of Letters Patent.

Patented Dec. 13, 1921.

Application filed July 29, 1919. Serial No. 314,112.

To all whom it may concern:

Be it known that I, GEOLEADYS G. THOMPSON, a citizen of the United States, residing at St. Louis, in the county of St. Louis City and State of Missouri, have invented certain new and useful Improvements in Garments, of which the following is a full, clear, and exact description, such as will enable others skilled in the art to which it appertains to make and use the same.

This invention relates to wearing apparel, and with respect to its more specific features, to loose-fitting outer garments for women, such as negligées or house gowns.

One of the objects of the invention is to provide an improved outer garment of the character mentioned which is simple in design, of attractive appearance, and which may be readily and inexpensively manufactured.

Another object is the provision of a simple form of material blank which is capable of quick transformation into a negligée garment constituting combined skirt and waist portions.

Other objects and advantages of the invention will be in part noted hereinafter in connection with the following description of the accompanying drawing, which illustrates a typical, and in certain respects preferred, embodiment of the invention, and in which—

Figure 1 is a front view of the improved finished garment;

Fig. 2 is a side view thereof; and

Fig. 3 is a plan of the blank, or an integral piece of material, from which the garment is made.

The garment as shown may include an integral piece of material of substantially rectangular shape when flat. This piece, which may be called a blank, is slitted longitudinally from one end for a distance more than the shoulder height of the wearer for whom the garment is designed. Thereby the blank constitutes a wide back panel 1 and two symmetrical front panels 2 and 3, each of the latter being one-half the width of the back panel. It will be understood that the edges of the material may be suitably hemmed or trimmed, as desired, and that when the cloth is sheer or light in weight, as is preferable, a suitable lining of silk or otherwise may be provided for both the front and back panels.

In transforming the blank into a garment

it is folded transversely, so that, on the wearer, the panel 1 hangs down the back and the front panels 2 and 3 may be crossed diagonally downward to afford a neck opening 4 and a front covering 5. These panels are then further wound so that the inner corners 6, 7 thereof meet at the bottom rear adjacent the back panel. That is to say, in use the two front panels are crossed over the breast of the wearer and wound downwardly about the wearer to bring the corners 6, 7 substantially behind the ankles. Readily detachable complementary fastening means 6' and 7', such as hooks and eyes, or snap fasteners, are applied to the panel corners 6 and 7, so that these parts may be easily secured together. Opposite points, such as 8 and 9, adjacent the sides of the back panel 1, are then drawn forwardly and draped over the respective crossing panels 2 and 3, to which the points 8 and 9 may be permanently stitched, if desired, or connected (similarly to the points 6, 7) by detachable fasteners 8' and 9' which respectively coat with complementary fasteners 8'' and 9''. Thus the panel 1 constitutes a back for the garment and affords arm holes 10 and 11 and side coverings 12 and 13. In addition, the inside of one front panel, such as 3, may be provided with snap fasteners 14' and 15' at points 14 and 15 to coöperate respectively with complementary fasteners 14'' and 15'' secured to the outside of the other panel, whereby, when the garment is in use, its adjusted position may be insured.

It will be apparent that if the sides 8 and 9 of the back panel are permanently stitched to the front panels 2 and 3, the garment may be donned as a coat; whereas if detachable fasteners are employed at these points and the panels 2 and 3 permanently stitched together at 14 and 15, it may be donned over the head of the wearer.

While, for purposes of simplification and cheapness, it may be desirable to form the garment of a one-piece unit, as described, it is to be understood, also, that the blank or the finished garment may be made up of separate sections of material, if desired; for example, the front panels may be of one material and the back panel may be of a contrasting or other material. In such modifications of course the separate pieces may be cut as desired and stitched together where necessary to constitute the unit described.

When the garment is donned it will be

noted that a most attractive arrangement thereof is possible. That is to say, for example, the crossing front panels 2 and 3 may assume a draped configuration to the 5 wearer, and the back panel as drawn about the sides may hang in graceful folds so that the whole, while loose fitting and allowing complete freedom of movement, yet agreeably fits the wearer and may assume, in general, a graceful and artistic shape and configuration. Finally, moreover, the ease of placing on the garment or removing it, the small space it may occupy when removed, and the relative inability of creases or folds 15 therein to mar its appearance when worn, renders the garment especially meritorious to fulfil the advantages and objects as hereinabove indicated.

Having described my invention, what I 20 claim as new and desire to secure by Letters Patent is:

1. A loose-fitting outer garment for women, including material of substantially rectangular shape and having one end longitudinally divided to constitute front 25 panels and having the other end whole to constitute a back panel, said front panels being sized to cross each other diagonally in front and wind around to meet at the bottom 30 rear for affording a neck opening and a front covering, fasteners to detachably secure together the meeting parts of said panels at the bottom rear, and said back panel having opposite side parts drawn 35 forwardly over said front panels and fastened to afford arm openings and lower side coverings.

2. A loose-fitting outer garment for women comprising an integral piece of material of substantially rectangular shape and of a length more than twice the shoulder 40 height of the wearer, said piece having one end longitudinally divided to constitute

symmetrical front panels and having the other end whole to constitute a back panel, 45 said front panels being adapted to cross diagonally and wind around to meet at the bottom rear for affording a neck opening and a front covering, fasteners to detachably secure together the meeting parts of 50 said panels at the bottom rear, and said back panel having outer edge points drawn forwardly over and secured to said front panels for affording arm openings and lower side coverings. 55

3. A unitary loose-fitting outer garment for women comprising a wide back panel and two narrower front panels, said front panels being sized to cross each other diagonally in front and wind around to meet 60 adjacent the back panel for affording a neck opening and a front covering, said back panel being of a width whereby opposite sides thereof may be drawn forwardly to 65 overlie the crossed portions of the front panels to afford arm openings and side coverings, and means to secure said parts of said back panel to said front panels.

4. A unitary outer garment for women, including waist and skirt portions, the back of the skirt and waist comprising a wide panel and the front of the skirt and waist comprising two narrower panels connected to the back panel adjacent the shoulders and extending downwardly to cross diagonally 70 in front and meet adjacent the bottom rear, the lateral lower portions of said wide panel being drawn forwardly to constitute side skirt portions partially inclosing said front 75 panels.

In testimony whereof I affix my signature, in the presence of two witnesses.

GEOLADYS GALE THOMPSON.
